Primary Examiner—A. Hugo Word*Assistant Examiner*—Lavone D. Tabor*Attorney, Agent, or Firm*—Milton L. Honig[57] **CLAIM**

The ornamental design for a toothbrush handle with stand, as shown and described.

DESCRIPTION

FIG. 1 is a perspective view of the new design assembled; FIG. 2 is a top plan view thereof;

FIG. 3 is a rear elevational view thereof;

FIG. 4 is a right side elevational view thereof, the left side being an identical mirror image thereof; and,

FIG. 5 is an exploded perspective view from above showing the toothbrush separated from the stand.

The bristle head shown in phantom in FIGS. 1, 4 and 5 forms no part of the new design.
